UNITED STATES PATENT OFFICE.

STEPHEN D. MYERS, OF CARROLLTON, TEXAS.

RAIL-JOINT SHOCK-ABSORBER.

1,109,862.

Specification of Letters Patent.

Patented Sept. 8, 1914.

Application filed November 14, 1913. Serial No. 800,996.

To all whom it may concern:

Be it known that I, STEPHEN D. MYERS, a citizen of the United States, residing at Carrollton, in the county of Dallas and 5 State of Texas, have invented certain new and useful Improvements in Rail-Joint Shock-Absorbers, of which the following is a specification.

My invention relates to a new and useful 10 rail joint shock absorber.

When a train is passing over a track, the rails of which are connected by the ordinary form of joint, each wheel of the train will slightly depress one of the abutting rail 15 ends of the joint before passing to the other rail end, thus communicating a frequently recurring shock or vibration to the cross-ties adjacent to the joint which will tend to eventually loosen the roadbed at this point.

20 It is the object of my invention to provide a means for resiliently supporting two abutting rail ends so as to eliminate what is commonly called a "low joint" and the vibratory effect above described.

25 Finally the object of my invention is to provide a device of the character described that will be strong, durable, simple and efficient and comparatively easy to construct and also one that will not be likely to 30 get out of order.

With these and various other objects in view, my invention has relation to certain novel features of the construction and use, an example of which is described in the 35 following specification, and illustrated in the accompanying drawing, wherein:

Figure 1 is a view in side elevation showing my novel shock absorber correlated with a rail joint. Fig. 2 is a view of the same 40 upon a smaller scale. Fig. 3 is a transverse sectional view of the same taken upon the line X—X of Fig. 1.

Referring now more particularly to the drawing, wherein like reference characters 45 designate similar parts in all the figures, the numerals 1 and 2 respectively denote two abutting rail extremities which are supported by cross-ties 3. A pair of ordinary fish-plates 4 are bolted against the two sides 50 of the rail webs at the joint. Beneath the joint, a metal plate comprising parts 5, 6 and 7 is bridged between two ties 3^a respectively extending beneath the abutting rail ends. The portions 5 of said plate lie 55 respectively upon the ties 3^a, and are spaced slightly beneath the rail ends. The spikes

7^a which engage the rails 1 and 2 with the ties 3^a pass through the end portions of the members 5, and are not driven sufficiently deep in the ties to draw said rail ends down upon said members 5. The members 6 are vertically disposed and respectively contiguous to the opposite lateral faces of the ties 3^a. The member 7 is a horizontal connection between the lower 60 ends of the members 6 flush with the under faces of the ties and contiguous to the roadbed. In the rectangular aperture formed between the parts 6 and 7 and the rail ends, there is vertically mounted a coiled spring 65 8 abutting at its lower end upon the member 7 and at its upper end against a plate 9 contiguous to the bases of the abutting rail ends. In the top face of the plate 9 there is counter-sunk the head of a bolt 10 centrally disposed within the spring 8 and passing through the member 7. Upon the lower end of said bolt is screw-threaded a nut 11 which may be tightened against the member 7 to produce a compression in the 70 spring 8. It is thus seen that the abutting rail ends rest at their juncture upon the plate 9 which is in turn supported by the coiled spring 8.

The strength of the spring 8 and the 75 amount of compression to which it is subjected will be such that the weight coming upon the joint during the passage of a train over the same will be largely sustained by said spring 8. In case however the joint is 80 obliged, during the passage of a train, to sustain an extraordinary weight, the spring 8 will yield downwardly sufficient to permit the abutting rail ends to be supported by the ties 3^a. By thus resiliently supporting 85 the abutting rails of a joint, the spring 8 constituting the resilient support is made to absorb the greater part of the vibration 90 which is communicated to the joint during the passage of the train. The deleterious 95 effect of such vibration upon the roadbed at the rail joint is thus eliminated.

The invention is presented as including 100 all such modifications and changes as properly come within the scope of the following claims:

What I claim is:

1. In a device of the character described, the combination of two abutting rail extremities, of a plate disposed beneath said rail extremities bridging the two ties nearest adjacent to the joint, the central portion 110

of said plate being depressed between said ties, a coiled spring abutting at its lower end against the depressed portion of said plate and supporting the abutting rail ends 5 at its upper extremity, and means for adjusting the compression of said spring.

2. In a device of the character described, the combination with two abutting rail extremities, of a plate disposed beneath said 10 extremities and normally spaced therefrom, said plate being bridged between the two ties nearest adjacent to the joint and having its center portion depressed between said ties, a coiled spring having its lower end 15 abutting upon the depressed central portion of said plate and supporting the two rail

ends at its top, a plate interposed between the rail ends and the top of said spring, a belt passing centrally through the spring having its head counter-sunk in the top of 20 said plate and having its lower end projecting through the central portion of said plate and a nut screw-threaded upon said bolt adapted to be tightened against the central portion of said plate.

25

In testimony whereof I have signed my name to this specification in the presence of two subscribing witnesses.

STEPHEN D. MYERS.
